DESIGN FOR A SHOE

Charles Morali, Forest Hill, N. Y., assignor to Delman, Inc., New York, N. Y., a corporation of New York

Application January 2, 1934. Serial No. 50,279

Term of patent 3½ years

To all whom it may concern:

Be it known that I, CHARLES MORALI, a citizen of the United States, residing in Forest Hill, Long Island, in the county of Queens and State of New York, have invented a new, original, and ornamental Design for a Shoe, of which the following is a specification, reference being had to the accompanying drawing, forming part thereof.

Fig. 1 is a perspective view showing one side of the shoe of the present design.

Fig. 2 is a perspective view showing the other side of the shoe.

The ornamental gems which are here shown as rhinestones may be white or any other color, or may be in assorted colors.

I claim:

The ornamental design for a shoe, as shown and described.

CHARLES MORALI.
